UNITED STATES PATENT OFFICE.

ERWIN HERMANN JAHNZ, OF WESTEND, NEAR BERLIN, GERMANY, AS
SIGNOR TO DEUTSCHE TELEPHONWERKE R. STOCK & CO., GESELL-
SCHAFT MIT BESCHRÄNKTER HAFTUNG, OF BERLIN, GERMANY.

CASH-REGISTER.

SPECIFICATION forming part of Letters Patent No. 689,971, dated December 31, 1901.

Application filed August 29, 1901. Serial No. 73,654. (No model.)

To all whom it may concern:

Be it known that I, ERWIN HERMANN JAHNZ, engineer, a subject of the King of Prussia, German Emperor, residing at Westend, near Berlin, Germany, have invented certain new and useful Improvements in Cash-Registers; and I do hereby declare that the following is a clear and exact description of the same.

In many cash trades—for instance, public houses, &c.—the individual amounts which the purchaser pays are always small. Moreover, they usually increase by five cents at a time. For this purpose it is quite sufficient for the cash-register to have only the following eleven keys, viz: a five-cent key and a dollar key and nine other keys for ten cents, twenty cents, &c., up to ninety cents. Owing to the small number of keys certain advantages are attained in the present invention which are unattainable in the much more complicated cash-registers of the usual kind. The dollar and the five-cent keys are each provided with two levers on opposite sides of the register and connected with each other. It is thus possible, on the one hand, to show exactly the same numerical record on the seller's side as on the purchaser's, and, on the other hand, to couple the five-cent key with the others in a very simple manner.

The improved cash-register is illustrated in the accompanying drawings, in which—Figure 1 is a side elevation, and Fig. 2 a plan view. Figs. 3 and 4 show details of the mechanism.

The lever *a* of the five-cent key is firmly lodged on one end of the shaft *b*, to the other end of which is attached a second lever *c*. The two levers *a* and *c* have arms *d*, which support the bar *e*. A rigid frame is thus formed, comprising the levers *a* *c*, the shaft *b*, and the bar *c*. Over the shaft *b* is placed a tube *f*, Fig. 4, which incloses with an oval slot one lever *g* of the dollar-key. On the tube *f* is keyed a disk *o*, with a lateral pin *p*, which engages a small slot *q* in the lever *g*. In consequence of this arrangement it is possible to pull out the key *g*; but, on the other hand, the tube *f* is forced to turn every time the key *g* is depressed. The second lever *h* of the dollar-key is keyed on the tube *f*. The

other key-levers *i*, Fig. 3, are independently pivoted on the tube *f*, and for the purpose of coupling with the key-coupler *j* are movable in the direction of a recess *k*, provided in their ends, as is more particularly described in my United States Letters Patent No. 676,386. If the five-cent key or the dollar-key is depressed, a lever on the right side of the register and at the same time another lever on the left side are raised. In this manner indicating-signals are raised in the usual manner, always two being raised. Of these two indicators of the five-cent key that raised by the lever *a* is only visible from the salesman's side and that raised by the lever *e* only from the purchaser's side, and likewise with the dollar-key. Consequently on both sides of the register the figures appear correctly—for instance, "\$1.65"—and not, as was the case in former cash-registers, on the purchaser's side correctly—viz., "\$1.65"—and on the salesman's side "56.1\$." The bar *e* according to the present invention serves at the same time for coupling the key-levers *i* with the five-cent key. For this purpose the arms *l* of the levers *i*, which coöperate in the usual manner with ratchet-pendulums *m*, are provided with projections *n*. These latter engage during the longitudinal movement of the levers *i* over the bar *e*. If it be desired to register five cents, twenty cents, thirty cents, &c., or one dollar, it is merely necessary to depress the corresponding key, without drawing it out. If, on the other hand, it is wished to register the sum of twenty-five cents, for instance, the twenty-cent key is pulled out and then pressed down. The five-cent key does not then require to be actuated direct, as it is automatically depressed by the projection *n* of the twenty-cent key. The lever *g* of the dollar-key has no projection *n*. If it is desired to register a sum over one dollar—for instance, one dollar and thirty cents—the dollar-key is preferably first pulled out and the thirty-cent key depressed. The dollar-key is thereby taken along with it by means of the key-coupler. If it is desired to register one dollar and thirty-five cents, the dollar-key and the thirty-cent key are first pulled and then the latter pressed down or the thirty-cent key

first pulled out and the dollar-key depressed. Both the keys are thus connected by means of the key-coupler. The five-cent key is taken along by means of the projection n of the 5 drawn-out thirty-cent key. If there were also a projection n on the lever g of the dollar-key, the simple coupling of the dollar-key with the thirty-cent key above described would not be possible. By pulling out the 10 dollar-key there would then be added to the value of the key next depressed one dollar and five cents instead of one dollar.

Having now described my invention, what I claim as new, and desire to secure by Letters 15 Patent, is—

In a cash-register the combination of a five-cent key, having two levers a , c on opposite sides of the register and connected by a bar e , a plurality of keys i for ten, twenty up to ninety cents provided with projections n in 20 proximity to the bar e , and a dollar-key, having two levers g , h on opposite sides of the register, substantially as set forth and described.

In witness whereof I have hereunto set my 25 hand in presence of two witnesses.

ERWIN HERMANN JAHNZ.
